(57) **CLAIM**

The ornamental design for a shear spring for a suspension, as shown and described.

DESCRIPTION

FIG. 1 is a perspective view showing the top, front, and right side of a shear spring for a suspension having the inventive design;

FIG. 2 is a front elevational view of the shear spring for a suspension shown in FIG. 1;

FIG. 3 is a back elevational view of the shear spring for a suspension shown in FIG. 1;

FIG. 4 is a top view of the shear spring for a suspension shown in FIG. 1;

FIG. 5 is a bottom view of the shear spring for a suspension shown in FIG. 1;

FIG. 6 is a left side elevational view of the shear spring for a suspension shown in FIG. 1; and,

FIG. 7 is a right side elevational view of the shear spring for a suspension shown in FIG. 1.
